CLAIM

The ornamental design for a spacer for inhaler, as shown and described.

DESCRIPTION

FIG. 1 is a perspective view of a spacer for inhaler showing a first embodiment of our new design, FIG. 2 is a front view of the spacer for inhaler of FIG. 1, FIG. 3 is a side view of the spacer for inhaler of FIG. 1, FIG. 4 is a top view of the spacer for inhaler of FIG. 1, FIG. 5 is a bottom view of the spacer for inhaler of FIG. 1, FIG. 6 is a perspective view of a spacer for inhaler showing a second embodiment of our new design, FIG. 7 is a front view of the spacer for inhaler of FIG. 6, FIG. 8 is a side view of the spacer for inhaler of FIG. 6, FIG. 9 is a top view of the spacer for inhaler of FIG. 6; and, FIG. 10 is a bottom view of the spacer for inhaler of FIG. 6. The broken lines in the drawings illustrate portions of the spacer for inhaler that form no part of the claimed design.

1 Claim, 10 Drawing Sheets
